J. C. McLAUGHLIN.
UNIVERSAL GOLF CLUB;
APPLICATION FILED JULY 21, 1916.

1,253,700.

Patented Jan. 15, 1918.

UNITED STATES PATENT OFFICE.

JOHN C. McLAUGHLIN, OF EAST ORANGE, NEW JERSEY.

UNIVERSAL GOLF-CLUB.

1,253,700.

Specification of Letters Patent. Patented Jan. 15, 1918.

Application filed July 21, 1916. Serial No. 110,481.

To all whom it may concern:

Be it known that I, JOHN C. McLAUGHLIN, a citizen of the United States, and a resident of East Orange, county of Essex, 5 and State of New Jersey, have invented certain new and useful Improvements in Universal Golf-Clubs, of which the following is a specification.

My invention relates more particularly 10 to golf clubs wherein a plurality of detachable striking faces are provided, one of which may be attached to the club at a time so that the club may represent a putter, a driver, mashie or other club according to 15 the striking face attached to the head.

I am aware that golf clubs of various kinds have been devised wherein the angle of the striking face may be varied, but I am not aware that clubs wherein the length 20 of the shaft can be varied to correspond with the angle of the striking face have been devised. The object of my invention is to provide a club wherein the angle of the striking face on the head of the club may 25 be varied by having the striking face detachably secured to the head. Preferably, several striking faces may be provided, any one of which may be attached to the head and at the same time I provide means 30 whereby the length of the shaft may be varied to correspond with the particular striking face attached to the head. By this method I am enabled to provide in a single universal golf club a club adapted, with 35 slight adjustment, to represent any one of the usual clubs required by the golfer. The advantage of a club of this kind is obvious, because the player with such a club is not required to carry a heavy golf bag equipped 40 with a half a dozen or more separate clubs.

The extra striking faces are small and comparatively light and, therefore, can readily be carried in the pocket. The striking faces are, in the present instance, readily attached 45 or detached from the head and the shaft, by simple manipulation, can be elongated or shortened to correspond with the striking face the player desires to use for making any particular shot. I thus provide a single 50 club which may quickly be adjusted to represent any club in the bag.

Furthermore, I have found that a great many players prefer the lie and balance of a wooden club or a club with a broad head 55 and can get better results therefrom. For this reason I have preferably designed my

improved universal golf club along the lines of the wooden club and the club head may be made of wood or metal, preferably aluminum, as shown in the drawings.

60

In the accompanying drawings,

Figure 1 shows the complete club with a striking face attached.

65

Fig. 2 shows an end view of the club head, the shaft being broken away.

70

Fig. 3 shows a side view of the club head with the striking face removed.

Fig. 4 represents a top view of the head partially in cross-section to show the attachment of the striking face thereto.

75

Fig. 5 represents the adjustable shaft with the upper slideable member in section.

Fig. 6 represents a portion of the shaft, partially in section, showing the method of positively securing the two telescoping members together in adjusted position.

75

Fig. 7 is a transverse cross-section of the shaft on the line 7—7 of Fig. 6; and

Figs. 8, 9, 10 and 11 represent end views of different striking faces which may be 80 attached to the club head to represent the different forms of clubs.

85

Referring to the drawings, 1 represents the head of my improved golf club which is preferably broad and of the shape and style of the ordinary wooden club and may be made of wood, but preferably I have shown it as made of aluminum, the shank 2 being integral with the head and bored out at 3 to form a socket for attaching the head 90 to the shaft in the usual manner. Preferably, the head is also bored out transversely at 4 and 5 above and below the center to lighten the club or give it the requisite balance. The front side of the head is preferably faced off at an angle to the bottom of the club and provided with a dove tail groove 6 open at the outer end and provided with a latch spring 7 secured to the head in any suitable manner as by a screw 8, as will 100 be seen in Figs. 8 and 4 of the drawings. A striking face 9 is preferably faced off at the back and provided with a dove tailed tongue 9^a, adapted to fit the dove tail 6 in the club head, as indicated in Figs. 2 and 4 105 of the drawings. The outer end of the spring catch 7 is preferably bent at 10 to form a nose adapted to engage the shoulder of a notch 11 in the back of the dove tailed tongue of each striking face thereby holding the striking face in proper position of attachment to the head. It will be under-

95

100

105

110

- stood that the striking face may be secured to the head in any suitable or preferred manner but the method of attachment shown and described is preferable because of its simplicity. The end of the head at 12 is preferably provided with a recess wherein the tail or end 13 of the latch spring 7 is adapted to extend so as to bring it into position to be reached readily by the player 10 when it is desired to release and remove a striking face. A light spring extension 14 is adapted to assist in closing the opening back of the spring catch and thereby facilitate the operation of the device. I preferably 15 provide a plurality of striking faces adapted to fit the dove tail snugly, any one of which may be attached to the club head in order to provide the club desired by the player. The angles the respective striking 20 faces make with the bottom of the club may be varied to suit the requirements of any particular player so as to provide striking faces corresponding with the several clubs he ordinarily uses.
- 25 An extension shaft is secured to the club head 1 in any suitable manner as by means of a pin 15 through the shank 2, as indicated in Fig. 1 of the drawings. In the present instance the lower part of the handle shaft 30 16, which is secured to the head of the club, is of wood covered with a casing 17 of thin sheet metal or tubing, but obviously I may use the wood without the tubing cover or tubing without the wood if desired. Telescoping over this is another tubular member 18 adapted to snugly fit the member 17, as indicated in Fig. 5 of the drawings. Obviously, in a club of this kind, it is necessary that the respective members of the longitudinal 35 40 adjustable shaft shall not turn or become displaced circumferentially while in use. To avoid this I preferably provide the lower tubular member 17 with a longitudinal groove 19 in which a tongue 20 snugly fits. Preferably the tongue 20 is formed by an inward longitudinal corrugation of the outer tube member 18, as indicated in Figs. 1 and 7 of the drawings, although I do not wish to be limited to this construction. By 45 50 this means the shaft may be extended to the desired length within the limits of the telescoping members while maintaining the members against twisting or circumferential displacement either with relation to each other or to the head of the club. Obviously, this is an important feature of my improved club because it is desirable that the club during use will be rigid in all its parts.
- The telescoping members after adjustment 55 60 may be secured together in any desired manner, but preferably I have provided a plurality of holes 21 in the inner tube 17, the holes for convenience being located longitudinally in the bottom of the groove 19, as indicated in Figs. 5 and 6 of drawings. The outer telescoping tube 18 is preferably provided with a single hole through the corrugation 20 in position to register with the holes 21 in the tube 17. Above this hole I preferably secure a tubular boss or lug 22 to the outer tube and through the boss and the hole in the tube 18 I pass a pin 23 adapted, when in register, to slide into and snugly fit the holes 21 of the inner tube 17, as indicated at 24 in Figs. 6 and 7 of the drawings. The outer end of this pin 23 is preferably provided with a head which is grooved circumferentially at 26 and a pair of spring actuated fingers 25 are adapted to engage the groove in the pin at 26, as indicated in Fig. 7 of the drawings. The fingers 25 preferably extend around the shaft, as indicated in Fig. 7 of the drawings, and are integral with a leaf spring 27 secured, by solder or otherwise, to the wall of the outer telescoping tube 18 at 28 and 29, as indicated in Fig. 6 of the drawings. The spring member 27 and the fingers 25 secured thereto are preferably spaced away from the tube 18 on the side opposite the pin 23 so as to 70 75 permit the spring to be pressed inward and carry the pin 23 outward to disengage the latter from the holes 21 when it is desired to shift the telescoping members to obtain a new adjustment of the length of the club. 80 85 When the proper length is obtained, the spring member 25 is released and the action of the spring 27 will be such as to cause the pin 23 to reengage one of the holes 21 and positively lock the shaft members together. 90 95
- The handle shaft may be provided with the usual or any preferred form of grip at the upper end of the outer telescoping member. In the present instance I have preferably attached a cork grip 30 to the upper 100 end of the telescoping tube 18. A ferrule is preferably attached to the tube at the lower end of the grip and a ring or cap 32 attached to the outer end of the tube, these being adapted to hold the cork grip in proper position and give a finish to the handle. Obviously, the grip may be glued or otherwise secured to the tubular shaft and leather or rubber may be used for the grip, if preferred.
- The operation of the club will be understood from the preceding description, but briefly may be described as follows: Taking the club head in the hand the player can remove the striking face by pressing down 110 115 on the tail 13 of the spring 7, thus releasing the latch from the notch 11 in the back of the striking face already attached to the head. The striking face can then be removed by sliding it longitudinally and a new striking face inserted, the player being particular to select the angle of face required whether it be putter, mashie, midiron or other club, it is desired to use. After selecting and attaching the striking face desired, the shaft 120 125 130

is then adjusted as to length to correspond with the striking face. This is done by pressing with the fingers on the spring 27 opposite the pin 23, thus lifting the pin out of the hole 21 in the lower member of the shaft, after which the outer telescoping member 18 may be slid either in or out to shorten or lengthen the shaft to correspond with the striking face attached to the head. When 10 the proper length is reached, the fingers are released from the spring 27 and the latter will force the pin 23 to enter one of the holes 21 and thus securely lock the parts together and the club is ready for use.

15 I do not wish to be limited to the specific details of construction herein shown and described for obviously these may be varied to suit the requirements of various players and different shaped heads may be used as well 20 as different forms of telescoping shafts without departing from the spirit and scope of my invention.

I claim:

1. A universal golf club comprising a 25 head, the striking face of which may be changed to vary the angle thereof, a handle shaft and means for varying the length of the shaft to accord with the striking face of the club.

30 2. A universal golf club comprising a head, means for changing the striking face of the head to vary the angle thereof, a handle shaft and means for changing the length of the shaft to correspond with the 35 striking face on said head.

3. A universal golf club comprising a head, means for removably attaching striking faces of varying angles thereto, and an extensible handle shaft, the length of which 40 may be varied to correspond with the striking face on said head.

4. A universal golf club comprising a head, the striking face of which may be changed to vary the angle thereof, a telescoping handle shaft therefor, means for preventing circumferential displacement of the telescoping members of said shaft while permitting longitudinal adjustment thereof for varying the length to accord with the 50 striking face of the club, and means for securing the telescoping members in adjusted position.

5. A universal golf club comprising a head, means for changing the striking face 55 to vary the angle thereof, a handle shaft adapted to be lengthened or shortened to correspond with the angle of the striking face

attached to said head, and means for preventing relative displacement of the parts when adjusted.

6. A universal golf club comprising a head, a plurality of striking faces therefor, means for removably securing a striking face on said head, a handle shaft adjustable as to length to correspond with the particular striking face secured to said head, and means for holding the shaft to the adjusted length.

7. A universal golf club comprising a head, means permitting the angle of the striking face to be varied, a handle shaft composed of telescoping members, means for preventing torsional displacement of said members relative to each other and to the head, said members being relatively adjustable longitudinally to vary the length of the shaft to accord with the striking face of the club, and means for securing the members in adjusted position.

8. A universal golf club comprising a head, a handle shaft therefor composed of two members, one slideable upon the other, coöperating means integral with the respective members for preventing circumferential displacement of one member with respect to the other, and interlocking means for securing said members against longitudinal sliding of one member with respect to the other.

9. A universal golf club comprising a head, a handle shaft composed of two telescoping members one secured to said head and the other slideable to vary the length of the shaft, a rib and groove connection between said members adapted to permit longitudinal adjustment while preventing relative circumferential displacement of the members, and means for positively securing said members against relative longitudinal movement when the shaft is adjusted to the proper length.

10. A universal golf club comprising a head, a plurality of striking faces adapted to be removably attached to said head one at a time, the angles of the respective striking faces being different to represent different clubs, means for attaching a striking face to said head, a handle shaft secured to said head and adjustable as to length to correspond with the angle of the striking face attached to said head, and means for maintaining said shaft at its adjusted length.

JOHN C. McLAUGHLIN.
